COMBINED ELECTRONIC TEST PANEL AND NOTATION PAD

Paul V. De Luca, Port Washington, N.Y., assignor to
Porta Systems Corp., Port Washington, N.Y.

Filed June 9, 1970, Ser. No. 23,392

Term of patent 14 years

Int. Cl. D13—03

U.S. Cl. D26—13

FIG. 3

FIG. 1

FIG. 2

FIG. 1 is a top view of a combined electronic test panel and notation pad embodying my new design;

FIG. 2 is a front view of the combined electronic test panel and notation pad of FIG. 1; and

FIG. 3 is a side view of the combined electronic test panel and notation pad depicted in FIG. 1.

I claim:

The ornamental design for a combined electronic test panel and notation pad, substantially as shown.
